Specification for Design.

Patented Aug. 31, 1920.

Application filed July 19, 1919. Serial No. 312,103. Term of patent 14 years.

To all whom it may concern:

Be it known that I, WILLIAM A. HONEYMAN, a citizen of the United States, residing at the city and county of San Francisco, State of California, have invented a new, original, and ornamental Design for a Vehicle-Operator's Heel-Rest, of which the following is a specification, reference being had to the accompanying drawing, forming part thereof, wherein—

Figure 1 is a view in perspective illustrating my new design.

Fig. 2 is a transverse central sectional view.

Fig. 3 is a view in top plan.

I claim:—

The ornamental design for a vehicle operator's heel rest, as shown.

In witness whereof I have signed my name to this specification in the presence of two witnesses.

WILLIAM A. HONEYMAN.
